AUXILIARY DEVICE FOR THE PRODUCTION OF THE
HOLLOW CROWNS OF TEETH FROM CAST METAL

Filed June 14, 1926

UNITED STATES PATENT OFFICE.

WILHELM KOPP, OF WALSRODE, GERMANY.

AUXILIARY DEVICE FOR THE PRODUCTION OF HOLLOW CROWNS OF TEETH FROM CAST METAL.

Application filed June 14, 1926, Serial No. 116,027, and in Germany February 24, 1926.

The present invention relates to an auxiliary device for the production of hollow moulds for the manufacture of crowns for teeth from cast metal. The method of producing (hollow) gold crowns which has hitherto been generally usual has consisted in utilizing so-called drawing or stamping apparatus for making the crowns. Since the casting process has been introduced into dentistry it has been the endeavor to discover a process permitting the production of gold crowns by said casting process. All methods hitherto employed, however, have proved to be imperfect and too tedious.

Now the present invention enables any person versed in the art to cast in the shortest time a crown which will suit all requirements.

The accompanying drawings show means for carrying the invention into use, and

Figure 1 is a side elevation of the complete device and

Figure 2 shows the essential parts separated.

The present invention consists in providing a pattern for the production of a thin-walled mould for the crown of the tooth which has the form of a rod and is made of steel or other material and which, as the accompanying drawing shows, is separable longitudinally into three or more parts. One end of this rod has the form of a human tooth while the other end is formed as a smooth stem. The several parts 1 and 2 of the pattern for the production of the mould for the crown are accurately ground on to one another at their contact faces and are held together in their correct positions by means of a sleeve or other closure device 3.

The method of producing a thin-walled mould for the manufacture of a crown by means of the pattern therefor is briefly as follows: The readily lubricated crown-end 1' of the pattern is dipped into molten wax so that it becomes covered with a thin layer of wax. When the pattern has been withdrawn from the molten wax, this thin layer of wax becomes stiff so as to form a thin-walled mould upon the pattern. The removal of

this wax-mould of the pattern is then effected by taking off the closure device 3 which holds the several parts 1 and 2 of the pattern together, whereupon the several parts, in the first place the central part 2, is withdrawn from the wax-mould. The wax-mould so obtained is embedded and the cast made therefrom by the usual method.

The crowns produced by means of the pattern of the crown possess a correctly anatomical form and have no seam or soldered joint. A further advantage is that places which are to be specially strengthened or the masticating faces, the backs, the cutting edges and so on of teeth which are to be given a special form may be varied by suitably modelling and applying wax on the mould before the latter is removed from the pattern.

The patterns for the crowns of teeth may be produced for any kind of tooth in the human jaw (for upper and lower incisors, bicuspids and molars).

Having now particularly described and ascertained the nature of my said invention, and in what manner the same is to be performed, I declare that what I claim is:

1. Process for forming moulds for the manufacture of hollow crowns of teeth from cast metal, consisting in forming a pattern for the crown of a tooth from several longitudinal parts, dipping this pattern into molten wax so as to coat it with a thin layer of wax, withdrawing the pattern together with this layer of wax from the molten wax, rendering stiff this layer of wax so as to form a hollow mould removing the pattern from this hollow mould by successively withdrawing first the middle and then the other longitudinal parts of the pattern.

2. Pattern for the production of thin-walled moulds for the crowns of teeth consisting of several bars, each being formed at its one end as a part of a tooth crown subdivided in the longitudinal direction of the tooth, a removable connecting device holding together these bars.

In testimony whereof I affix my signature.
WILHELM KOPP.
